Primary Examiner — Leanne Was-Englehart*Assistant Examiner* — Yelizaveta Y Masalimova(74) *Attorney, Agent, or Firm* — Banner & Witcoff, Ltd.(57) **CLAIM**

The ornamental design for a shoe as shown and described.

DESCRIPTION

FIG. 1 is a bottom photographic view of a shoe showing my new design;

FIG. 2 is a side photographic view thereof;

FIG. 3 is an opposite side photographic view thereof;

FIG. 4 is a front photographic view thereof;

FIG. 5 is a bottom view of the shoe of FIGS. 1-4 represented with line drawings to show the claimed design with more clarity;

FIG. 6 is a side view thereof;

FIG. 7 is an opposite side view thereof; and,

FIG. 8 is a front view thereof.

The broken lines and the greyed-out photographic area showing the remainder of the shoe form no part of the claimed design.
